CLAIM

The ornamental design for a waterproof electrical connector,
substantially as shown and described.

DESCRIPTION

FIG. 1 is a front elevational view of a waterproof electrical connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a top-front-right-side perspective view thereof.

The broken-line portion of the drawings is included only to
show unclaimed subject matter and forms no part of the
claimed design.
